(57) **CLAIM**

The ornamental design for a bathtub as shown and described.

DESCRIPTION

FIG. 1 is a perspective view of the claimed design;
FIG. 2 is a front view of the claimed design shown in FIG.
1;
FIG. 3 is a rear view of the claimed design shown in FIG.
1;
FIG. 4 is a side view of the claimed design shown in FIG.
1;
FIG. 5 is another side view of the claimed design shown in
FIG. 1;
FIG. 6 is a top view of the claimed design shown in FIG. 1;
FIG. 7 is a bottom view of the claimed design shown in FIG.
1; and,
FIG. 8 is a detailed view of the claimed design shown in
FIG. 1.

The ornamental design which is claimed is shown in solid
lines in the drawings. The broken lines in the drawings show
portions of the bathtub that form no part of the claimed
design. The dot-dash broken lines in the drawings depict
the boundary of the claimed design and form no part of the
claimed design. The dot-dot-dash broken lines shown in
FIGS. 1 & 8 define the boundary of the enlargement area and
form no part of the claimed design.

1 Claim, 7 Drawing Sheets
